LIQUID FUEL BURNER

Alexander Ottajovits, Vienna, Austria, assignor to
Robert Mahler, Vienna, AustriaApplication December 18, 1937, Serial No. 180,668
In Austria October 8, 1936

3 Claims. (Cl. 158—75)

This invention relates to the manufacture of burners of the type in which a liquid fuel is atomized by steam.

The object of the present invention is to provide an improved burner of the type indicated which, whilst enabling the steam supply and the liquid fuel supply to be controlled simultaneously and in dependence upon one another, will allow of adjustment of the steam supply relatively to the liquid fuel supply by simple means without the use of stuffing boxes, glands or the like.

A liquid fuel burner of the type in which the fuel is atomized by steam according to the present invention comprises a steam nozzle and an oil nozzle coaxially arranged one within the other, and a flexible diaphragm connecting said steam nozzle and said oil nozzle and allowing relative movement between said steam nozzle and said oil nozzle. The burner according to the present invention may further comprise means for adjusting said steam nozzle relative to said oil nozzle, an oil regulating needle coacting with said oil nozzle, a steam throttle member adapted to regulate the steam supply, and an actuating member adapted to act simultaneously on said oil regulating needle and on said steam throttle member.

According to a further feature of the invention, an annular chamber may be provided surrounding the oil nozzle and formed by an enlargement of the steam supply channel between said steam throttle member and said steam nozzle to enable the throttled steam to expand therein before entering the nozzle, the flexible diaphragm sealing said annular chamber against steam escape.

The accompanying drawing, which illustrates one form of burner constructed in accordance with the invention shows a burner in longitudinal section.

As shown, the steam and oil nozzle members are concentrically arranged one in the other in such a way that the steam nozzle member E surrounds the oil nozzle member F. The steam nozzle member E comprises a steam nozzle 13 and the oil nozzle member F comprises an oil nozzle 10, the steam and oil nozzles being coaxial owing to the concentric arrangement of the steam and oil nozzle members. The steam nozzle 13 surrounds the oil nozzle 10 so that a steam nozzle channel 8 is formed between them.

The steam is throttled before entrance into the actual steam channel 8 at the throttling place 9 and the steam supply regulated there in dependence on the oil supply. The quantity

of steam passing through 9 is regulated by the throttling member 17 which, in the embodiment illustrated, is constructed as a regulating plunger and is moved into the open position by a spring 18 and into the shut position against the action of this spring in the manner hereinafter described. The throttling is for the purpose of giving the steam an opportunity of expanding in a closed chamber before emerging from the steam nozzle whereby an effect of diminution in noise 10 is obtained similarly as in internal combustion engine silencers. The throttling of the steam supply regulation therefore does not take place directly at the steam nozzle opening, but much further back, leaving a suitable space for expansion between the throttle 9 and the nozzle opening. This space comprises an enlarged portion formed in the steam nozzle member E between the steam nozzle channel 8 and the throttle 9, constituting an annular steam expansion chamber 16 surrounding the oil nozzle member F.

The quantity of oil emerging at any time from the oil nozzle 10 is regulated by an oil regulating needle 11 which throttles the free passage cross section to a greater or less extent, the needle 11 being moved by means of a spring 12 into the open position and against the action of this spring into the closed position in the manner hereinafter described.

The nozzles 10, 13, open into a mixing chamber 14, which is fitted with a primary air regulating disc 15. The disc 15 is provided with perforations and by rotation of the disc 15 these can be brought into register with corresponding 35 perforations in the rear wall of the casing of the mixing chamber, whereby the admission of atmospheric air into the mixing chamber 14 can be regulated by a "hit-and-miss" action.

The adjustment of the oil regulating needle 40 11 and the steam throttling member 17 takes place through a common actuating member, e. g., a small hand wheel 19. The hand wheel 19 is secured to a housing 20 which, in turn, is connected with a regulating disc 21, the parts 19, 45 20 and 21 normally forming an integral unit. The regulating disc is rotatable on the oil nozzle member F by means of a screw thread 22 and is thereby displaceable in an axial direction. The inward and outward movement of the regulating 50 disc 21 is limited by lateral abutment of a finger 35, rigidly secured to the disc, against the stops 36 and 37 being respectively an upward and a downward projection on a washer 38 and a washer 39. Both washers are mounted on the 55

oil nozzle member F and in use are kept firmly in position by a nut 40. By means of this nut 40, the relative position of the stops 36 and 37 can be adjusted by rotating the washers 38 and 39 5 relative to each other. The finger 35 is allowed movement intermediate of the two stops i. e., in the position of the stops illustrated in the figure, half a revolution.

The regulating disc 21 engages a plunger 23 10 which moves the throttling member 17 into closed position against the action of the spring 18 when the small hand wheel 19 is actuated to screw the disc 21 onto the oil nozzle F.

The regulation of the oil regulating needle 11 15 is carried out by means of a plunger 24 carried in the oil nozzle member and projecting into the housing 20, where it is engaged by an adjustable oil regulating screw 26 disposed in a protective casing 25. The needle 11 and plunger 24 20 comprise an oil control pin or valve member.

The operation of the burner is as follows:—

The oil regulating needle 11 and the steam throttling member 17 are held in the open position by the springs 12 and 18 respectively. In 25 this position the largest cross sections are freed for the passage of the steam and the oil. If now the small hand wheel is rotated, the regulating disc 21 moves the plunger 23 to the left, whereby the throttle member 17 is displaced to 30 the same degree, and the passage of the steam is correspondingly throttled. At the same time the oil regulating screw 26 strikes against the plunger 24, whereby the quantity of oil being atomized is 35 adjusted. When the small hand wheel 19 is turned back, the steam and oil regulating members 17 and 11 are again moved to the right by the springs 18 and 12 respectively through a distance corresponding to the amount the small hand wheel has been turned back, whereby a 40 correspondingly larger quantity of oil and steam is admitted to the mixing chamber 14.

The steam throttled by the throttling member 17 expands in the space between the throttle member and the nozzle opening, the steam chamber 45 16 being formed as an annular enlargement of this space surrounding the oil nozzle member F, so that a remarkably noiseless working of the burner is made possible.

A further characteristic of the invention consists in the two nozzle members being axially displaceable relatively to one another. This is 50 obtained by a flexible connection of the two nozzle members which permits the oil nozzle member to be axially slid in the steam nozzle member, whilst ensuring at the same time a perfect seal of the steam conduits against steam escape. In the embodiment illustrated in the figure a diaphragm 27 having its centre secured to the oil nozzle member F by a nut 30 is clamped at 55 its periphery between the steam nozzle member E and a clamping socket 28 both rigidly connected together by a screw 29. The clamping socket 28 is axially movable with respect to the oil nozzle member F by slidably engaging the latter at 60 31. Axial movement of the clamping socket 28 is effected by means of an externally screw-threaded adjusting sleeve 33 mounted to rotate on the oil nozzle member F, but prevented from axial movement thereon, the external thread of the adjusting 65 sleeve 33 engaging a female thread in an extension 32 of the clamping socket 28. By turning the adjusting sleeve 33 the clamping socket 28 can thus be moved in the desired direction, and owing to the rigid screw-connection of the 70 latter with the steam nozzle member E, and the

relative position of the steam nozzle 13, and the oil nozzle 10, and, hence, the cross-section of the steam nozzle opening is adjusted in the desired manner, thereby determining the ratio of steam and oil admission to the mixing chamber 5 14, and shaping the flame according to requirement. This adjustment is made possible by the yielding of the diaphragm 27, which also ensures a fluid-tight joint between the steam nozzle member E and the clamping socket 28, sealing 10 the steam expansion chamber 16 against steam escape. The adjustment can be made in either direction and even while the burner is in operation. Once the desired adjustment has been made, it can be fixed by tightening up a counter-nut 34.

It will be seen from the above description and from the drawing that, by unscrewing the screw 29, the burner can be dismantled into two parts, namely the steam nozzle member E and the parts 20 associated therewith and the oil nozzle member F and all the parts associated therewith. The oil regulating needle 11 can then be extracted after removal of the regulating disc 21 and unscrewing the necessary screw-connections. In 25 like manner, the steam throttle member 17 can be removed by screwing out of the steam nozzle member E the socket accommodating the throttle member 17. All parts are then readily accessible for cleansing and other purposes. On the other hand, it will be observed that the setting of the clamping socket 28 relative to the oil nozzle member F is retained by the locknut 34 remaining in position during dismantling. As dismantling the burner does not necessitate altering the setting 30 of the oil regulating screw 26, the oil regulating needle will also resume its original position on the burner being re-assembled. The same applies to the steam throttle member 17 which, as shown, has a shoulder abutting against an adjustable 35 cap closing the socket which accommodates the member 17, the cap being fixed in position by a lock nut. It is not necessary to remove this cap for the purpose of dismantling the burner and therefore the positioning of the steam throttle 4 member in the throttle place 9 also remains unaffected by the dismantling and reassembling of the burner.

It will also be clear from the foregoing that, owing to the provision of the adjustable cap on 5 the socket carrying the steam throttle member 17 and of the adjusting sleeve 33 determining the relative position of the oil nozzle 10 and the steam nozzle 13, and owing to the provision of the oil adjusting screw 26, each of these adjustments can be effected independently of the other. This will generally be done manually by way of pre-setting before operation, while the combined control of oil and steam supply by means of the handwheel 19 is intended for use 6 during operation, but the adjustment of the effective cross-section of the nozzle aperture by means of the adjusting sleeve 33 can also be effected during operation of the burner.

The oil is introduced into the oil nozzle member F through the space enclosing the spring 12, and no stuffing boxes, glands or the like are required. In the steam supply channel, and more particularly in the steam expansion chamber 16, the flexible diaphragm 27 serves as an effective seal against steam escape and, being flexible, enables stuffing boxes, glands or the like to be dispensed with.

I claim:—

1. A burner for liquid fuel of the type in which

the fuel is atomized by steam, comprising a steam nozzle and an oil nozzle arranged coaxially, a flexible membrane interconnecting said nozzles and permitting relative endwise movement therebetween, means for adjusting and securing in position said oil nozzle relatively to the steam nozzle, an oil control pin within and coacting with said oil nozzle, means for adjusting said oil control pin, a steam throttling member, means for adjusting said steam throttling member, the two last mentioned adjusting means having at least one common member through which the oil control pin and the steam throttling member may be actuated simultaneously by hand, means acting independently of the adjusting action of said common member for adjusting the oil control pin, the oil nozzle being capable of adjustment with respect to the steam nozzle under the action of the said means for adjusting and securing the oil nozzle in position relatively to the steam nozzle, without modification of the adjustment of the steam throttling member and the oil control pin.

2. A burner for liquid fuel of the type in which the oil is atomized by steam, comprising a steam nozzle and an oil nozzle arranged co-axially, a flexible membrane interconnecting said nozzles and permitting relative endwise movement therebetween, an oil control pin axially disposed within the oil nozzle, a spring tending to retract said pin, a steam conduit leading laterally to the steam nozzle, a steam throttling plunger, set off to one side of the axis of the steam nozzle, a spring tending to retract said plunger, a unit having a screw threaded mounting upon a non-rotative portion of the burner, said unit comprising a disk, a housing, and a manually operable member for bodily turning said housing, and

an adjusting screw axially disposed within the housing and adjustable endwise with respect thereto and bearing against the rear end of the oil control pin, the forward face of the disk being of an amplitude to overlie and engage the rear end of the steam throttling plunger.

3. A burner for liquid fuel of the type in which the fuel is atomized by steam, comprising a steam nozzle and an oil nozzle arranged co-axially, a flexible membrane interconnecting said nozzles and permitting relative endwise movement therebetween, an oil control pin axially disposed within the oil nozzle, a spring tending to retract said pin, a steam conduit leading laterally to the steam nozzle, a steam throttling plunger, set off to one side of the axis of the steam nozzle, a spring tending to retract said plunger, a unit having a screw threaded mounting upon a non-rotative portion of the burner, said unit comprising a disk, a housing, and a manually operable member for bodily turning said housing, an adjusting screw axially disposed within the housing and adjustable endwise with respect thereto and bearing against the rear end of the oil control pin, the forward face of the disk being of an amplitude to overlie and engage the rear end of the steam throttling plunger, a pair of circumferentially movable stops carried by the non-rotative portion of the burner, a projection carried by the disk and projecting between said stops, and means for binding said stops in varying position of circumferential adjustment to thereby determine the extent of rotation of the disk and consequently to determine the degree of adjustment of the oil control pin and the steam throttling plunger.

ALEXANDER OTTAJOVITS.
